VARIABLE CONDUCTANCE STANDARD

John A. Connor, Haddonfield, N.J., assignor to Leeds and Northrup Company, Philadelphia, Pa., a corporation of Pennsylvania

Application June 9, 1954, Serial No. 435,491

2 Claims. (Cl. 323—74)

This invention relates to differential loss networks which may be used as variable conductance units of general application and which are particularly suited as precision standards for alternating-current measurements.

Generally in accordance with the invention, a fixed resistance means is effectively transformed to a variable conductance standard by inclusion of the fixed resistance means in a composite network including adjustable reactances whose concurrent values determine the transformation. The equivalent or transformed conductance value is essentially constant throughout a range of frequencies. The reactances are so adjusted that the concurrent incremental changes of their energy-storage factors are of opposite senses and of such magnitudes that the total energy storage of the composite network is essentially constant throughout the range of adjustment of the reactances, the effective shunt conductance of the network, however, having different values, each precisely and reproducibly corresponding with concurrent values of the adjustable reactances.

More particularly, a precision standard of adjustable conductance is provided by a two-terminal network in which two adjustable reactances, specifically capacitors, are connected in series between the network terminals and are so mechanically coupled that their combined series-reactance remains essentially constant throughout the range of adjustment. A fixed resistance means is connected in parallel to one of the adjustable reactances. The equivalent shunt conductance of such network varies as a function of the reactance in shunt to the fixed resistance so that, if desired, the operating dial, or equivalent of the adjustable reactance, may be calibrated for direct reading of the equivalent shunt conductance values corresponding with the dial settings. The symmetrical pair of variable loss networks above briefly described may be used with or in measuring circuits of various known types for precise measurement of conductance by direct-substitution methods: they may be used, for example, in quality control measurements of capacitors, coils, cables and other high-frequency components.

For a more detailed understanding of the invention, reference is made to the subsequent description and to the attached drawings in which:

Figs. 1A and 1B show generalized forms of elementary networks;

Figs. 2A and 3A show series and parallel arrangements of an adjustable capacitor and a fixed resistance respectively corresponding with Figs. 1A and 1B;

Figs. 2B and 3B respectively represent the electrical equivalents of Figs. 2A, 3A;

Fig. 4 shows a composite network synthesized from networks of the type shown in Fig. 3A;

Fig. 5A illustrates a preferred form of the network shown in Fig. 4;

Fig. 5B represents the electrical equivalent of Fig. 5A;

Figs. 6 to 8 are graphs referred to in discussion of preceding and subsequent figures;

2

Fig. 9, in perspective, shows a variable conductance unit or standard;

Fig. 10, in perspective, shows the internal construction and components of the unit of Fig. 9;

Figs. 11 and 12 are graphs referred to in discussion of the unit of Fig. 9;

Fig. 13 schematically illustrates an alternative capacitor arrangement for the unit of Fig. 9;

Fig. 14 schematically illustrates a bridge circuit including composite conductance networks of preceding figures;

Fig. 15 schematically illustrates a Q-meter circuit utilizing composite conductance networks of preceding figures;

Fig. 16 schematically illustrates a bridge circuit including a pair of composite networks of type shown in Fig. 5A.

The networks shown in Figs. 4, 5A, 13 and 14 are composites of rudimentary networks which are first discussed in order that the invention in all of its various illustrated forms may be clearly understood.

Referring to Figs. 1A and 1B, a series-combination of resistance (R_S) and reactance (X_S) may be transformed into an equivalent parallel combination of resistance (R_P) and reactance (X_P), or, conversely, a parallel combination of resistance (R_P) and reactance (X_P) may be converted into an equivalent series-combination of resistance (R_S) and reactance (X_S), by means of the following relationships.

$$30 (1) \quad R_P = R_S(1 + Q^2)$$

$$(2) \quad X_P = X_S \left(1 + \frac{1}{Q^2}\right)$$

where

$$(3) \quad (3) \quad Q = \frac{X_S}{R_S} = \frac{R_P}{X_P}$$

For all cases in which Q is large compared to unity, the relationships expressed by Equations 1 and 2 may be more simply expressed as

$$(4) \quad (4) \quad \frac{R_P}{R_S} = Q^2$$

and

$$(5) \quad (5) \quad \frac{X_P}{X_S} = 1$$

The percent error introduced by use of the simpler approximate expressions (Equations 4 and 5) is given by the relationship

$$50 (6) \quad \epsilon = \frac{100}{1 + Q^2}$$

Specifically, for any value of Q greater than 20, the error is less than 1/4%.

When, as shown in Figs. 2A and 3A the reactances are capacitive, the transformation Equations 5 and 4 may be reduced to

$$(7) \quad C_S = C_P = C$$

$$60 (8) \quad (8) \quad R_S R_P = \frac{1}{\omega^2 C^2}$$

Referring now to Fig. 2A, the rudimentary network 10S comprises an adjustable capacitor in series with a resistor of fixed value R_S . It is electrically equivalent to Fig. 2B, the adjustment of capacitor C_S affording (as may be derived from Equation 8) adjustment of the equivalent parallel resistance R_P and therefore of the equivalent shunt conductance G_P in accordance with the relations

$$(9) \quad R_P = \frac{1}{(\omega C)^2 R_S} = \frac{G_S}{(\omega C)^2}$$

$$(10) \quad \frac{1}{R_p} = G_p = (\omega C)^2 R_s$$

It is to be noted that the adjustment of capacitor C_p affects both the energy-loss factor and the energy-storage factor of the network. More specifically, the adjustment of capacitance C_p changes not only the equivalent shunt conductance G_p of the network but also the equivalent shunt capacitance C_p . It is further to be noted that the value of capacitance C_p for a desired value of equivalent shunt conductance depends upon frequency.

Referring to Fig. 3A, the rudimentary network 10P comprises an adjustable capacitance C_p in parallel with resistance of fixed value R_p . This network is electrically equivalent to Fig. 3B, the adjustment of capacitance C_p affording, as may be derived from Equation 8, adjustment of the equivalent series-resistance R_s in accordance with the relation

$$(11) \quad R_s = \frac{1}{(\omega C)^2 R_p} = \frac{G_p}{(\omega C)^2}$$

It should be noted that the adjustment of capacitance C_p affects both the energy-loss factor and the energy-storage factor: more specifically, the adjustment of capacitance C_p changes not only the equivalent series-resistance R_s (Fig. 3B) but also the equivalent series-capacitance C_s . It should also be noted that the setting of adjustable capacitance C_p for any given value of the equivalent resistance R_s depends upon frequency. As later explained, these disadvantages of the rudimentary network 10P of Fig. 3A are eliminated in the corresponding composite resistance-transformation networks of Figs. 4, 5A and others subsequently described.

Referring to Fig. 4, the network 20P is a series combination of two networks 10P of Fig. 3A in which adjustable capacitors C_{p1} , C_{p2} are oppositely adjusted to maintain constancy of their equivalent total reactance as seen at the network terminals. Under such conditions, the effective loss variation provided by adjustment of the capacitors is the difference between the conductance variations provided by the two elementary loss networks acting as a differential combination and also as will be shown, such variation of effective loss factor is not a function of frequency. The composite network 20P is therefore free of the two principal disadvantages of the elementary network 3A.

The network 20P of Fig. 4 comprises two serially-connected networks, each of which is similar to network 10P of Fig. 3A in that it is a parallel combination of fixed resistance and adjustable capacitance.

The equivalent series-resistance of network 20P is comprised of two portions respectively related to G_{p1} and G_{p2} , each in manner above explained in discussion of Figs. 3A, 3B. Thus, the total equivalent series-resistance R_T of network 20P (as found by applying Equation 9) is

$$(12) \quad R_T = \frac{1}{\omega^2} \left(\frac{G_{p1}}{C_{p1}^2} + \frac{G_{p2}}{C_{p2}^2} \right)$$

The total capacitance of network 20P is

$$(13) \quad C_T = \frac{C_{p1} C_{p2}}{C_{p1} + C_{p2}}$$

The corresponding total elastance of network 20P is

$$(14) \quad S_T = \frac{C_{p1} + C_{p2}}{C_{p1} C_{p2}} = S_{p1} + S_{p2}$$

where

$$S_{p1} = \frac{1}{C_{p1}}$$

and

$$S_{p2} = \frac{1}{C_{p2}}$$

Expressing the capacitances in terms of elastances, Equation 12 may be rewritten as

$$(15) \quad R_T = \frac{1}{\omega^2} (G_{p1} S_{p1}^2 + G_{p2} S_{p2}^2)$$

The equivalent total conductance G_e (Fig. 5B) by analogy to Equation 10 with capacitances expressed in terms of elastances may therefore be written as

$$(16) \quad G_e = \frac{R_T \omega^2}{S_T^2}$$

By substitution of Equation 15 in Equation 16

$$(17) \quad G_e = G_{p1} \left(\frac{S_{p1}}{S_T} \right)^2 + G_{p2} \left(\frac{S_{p2}}{S_T} \right)^2$$

As appears from Equation 17, the equivalent shunt conductance of network 20P (Fig. 4) does not depend upon frequency.

The network P20 of Fig. 5a is the same as network 20P of Fig. 4 except that the resistor in shunt to capacitor C_{p2} is omitted, i.e., G_{p2} of Fig. 4 is made of infinite value in network P20 of Fig. 5a. This affords the maximum difference between the loss variation of the two rudimentary networks of network 20P (Fig. 4) as effected by adjustment of capacitors C_{p1} , C_{p2} . For the composite network P20 of Fig. 5a, Equation 17 reduces to

$$(1) \quad G_e = \frac{G_{p1} S_{p1}^2}{S_T^2}$$

Since C_T and G_{p1} are constant, adjustment of the two capacitors of network P20 (Fig. 5a) provides a change of the equivalent shunt conductance (G_e of Fig. 5B) which is independent of frequency. Moreover, such adjustment does not affect the total shunt capacitance (C_T of Fig. 5B). Thus the composite network P20 of Fig. 5a is free of the two principal limitations of the rudimentary network 10P of Fig. 3A.

As appears from the previous discussion of Figs. 4, 5A and 5B, Equation 18 is the basic design equation for conductance standards or units. Since for a particular

unit the conductance G_{p1} may be of fixed value, and since the total elastance of the adjustable capacitors is maintained at fixed values, Equation 18 may be rewritten in simpler form as

$$(45) \quad (19) \quad G_e = K S_{p1}^2$$

where

$$K = \frac{G_{p1}}{S_T^2}$$

50 For an adjustment of the capacitors which effects an incremental increase of elastance of capacitor C_{p1} , the corresponding new value of the equivalent shunt conductance G_e (Fig. 5B) is

$$(55) \quad (20) \quad G_e + \Delta G_e = K (S_{p1} + \Delta S_{p1})^2$$

By subtraction of Equation 19 from Equation 20, it thus appears that

$$(21) \quad \Delta G_e = K [(S_{p1} + \Delta S_{p1})^2 - S_{p1}^2]$$

60 The relative change in the equivalent shunt conductance of the standard for such adjustment is therefore

$$(22) \quad \frac{\Delta G_e}{G_e} = \left(1 + \frac{\Delta S_{p1}}{S_{p1}} \right)^2 - 1$$

Such relationship is shown by curve A of Fig. 6.

In construction of conductance units or standards of the types shown in Fig. 5A, there are limiting factors to be considered. Again assuming that the permissible error should not be greater than $1/4\%$, Q , as defined in Equation 4, should not be less than 20. Such assumption imposes the requirement that for the lowest frequency used, quotient

$$\frac{C_T}{G_e}$$

is limited to such values that

$$(23) \quad \frac{C_p}{G_e} > \frac{3.2}{f}$$

where

G_e is in micromhos
 C_T is in micromicrofarads
 F is in megacycles

Additionally assuming that C_T will ordinarily be no greater than about 250 mmf., which is sufficiently large to assure negligible stray capacitance effects and yet is sufficiently small for parallel substitution measurements, a rough maximum-value limitation of G_e may be set at about 80 micromhos for one megacycle, 8 micromhos for 100 kilocycles (see curve B2, Fig. 7). These assumptions also limit the value of R_{P1} since the maximum value of G_e is less than but within a few percent of the conductance value G_{P1} of resistor R_{P1} . After selection of a value of G_e within the allowed range and with knowledge of the maximum

$$\frac{\Delta S_p}{S_p}$$

afforded by the selected capacitors, the maximum relative change of G_e can be computed from Equation 18 or ascertained from curve A of Fig. 6.

A calibration curve of dial settings vs. equivalent shunt conductance may be made by measurement of C_{P1} and C_{P2} and substituting the measured values in Equation 18 for solution of the corresponding values of G_e . Curves C_{P1} and C_{P2} of Fig. 8 are examples of curves so plotted in terms of capacitance; the fixed resistance means used had a conductance of 50 micromhos (20,000 ohms) and the total capacitance C_T was kept constant at 250 mmfs. From this data can be plotted a G_e curve in terms of dial setting.

A two-range adjustable conductance unit DG embodying the composite network P20 of Fig. 5A is shown in Figs. 9, 10. The terminals 30A, 30B are connected to the metal housing 31 to provide two ground terminals corresponding with terminal 30 of Fig. 5A. The terminals 32A, 32B are connected to each other to provide two "high" terminals corresponding with terminal 32 of Fig. 5A. The two sets of terminals are provided so that as later appears in discussion of Figs. 14 and 15, one pair of terminals may be connected to a detector or measuring network with the "unknown" substituted across the other pair of terminals.

The dial 11G of unit DG is mechanically connected through an insulated coupling 35 to the rotor shaft of adjustable condenser 34. This shaft is electrically and mechanically connected to the rotor shaft of a second adjustable condenser 36. These two condensers, corresponding with adjustable capacitors C_{P1} and C_{P2} of Fig. 5A, are connected in series between the ground and "high" terminals of the unit. The plates of the condensers 34 and 36 are so oriented that as the capacity of one condenser is increased, the capacity of the other is decreased. However, none of the commonly available adjustable capacitors, i.e., those of the linear capacitance, straight-line frequency, or straight-line wavelength types continuously affords the desired relation defined in Equations 13, 14. For unit DG, a satisfactory compromise was obtained by padding two straight-line frequency capacitors 34, 36 with adjustable fixed capacitors 39, 40. The resulting elastances and condition of tracking are shown in Fig. 11 in which the curve of total elastance S_T is plotted from the sum of the measured reciprocal capacitances (elastances) S_{P1} and S_{P2} of the individual condensers 34, 36 for the various settings of their operating dial 11G. The switch 41 (Fig. 10) is operable by knob 42 (Fig. 9) selectively to connect one or the other of fixed resistors 43A, 43B in shunt to condenser 36. Each of

resistors 43A, 43B corresponds with resistance R_{P1} (conductance G_{P1}) of Fig. 5A.

These resistors are of low reactance type such as disclosed, for example, in United States Letters Patent Nos. 1,972,499, 1,972,720 and 2,199,810. The resistance values of these resistors (43A, 43B) in the particular unit shown in Figs. 9 and 10 were 100,000 and 50,000 ohms respectively.

Using these two resistors, the calculated incremental conductance ranges of unit DG are shown by the curves G_{e1} and G_{e2} of Fig. 12. The correspondence between the calculated and measured values is so close that curves of the measured values are not drawn.

All conductance measurements made for check of the calculated calibration curves were made by reactance variation techniques described by D. B. Sinclair in the I.R.E. Proceedings, volume 26, No. 12, December 1938. Such techniques though precise are tedious and time-consuming which emphasizes the need for a simple direct substitution standard of shunt conductance such as afforded by unit DG.

The need for padding condensers to obtain constancy of the total elastance of an adjustable conductance standard may be avoided by using an adjustable condenser of the type schematically illustrated in Fig. 13. In this type of dual adjustable capacitor, the intermeshing area of the fixed and movable plates is constant but the spacings between each movable plate 50 and the associated stator plates 51A, 51B are complementarily adjustable.

With such construction, the elastance of capacitance C_{P1} is

$$(24) \quad S_1 = N \frac{d}{A}$$

where

A is plate area
 d is interplate spacing
 N is a constant

and of condenser C_{P2} is

$$(25) \quad S_2 = N \frac{D-d}{A}$$

where D is a total interplate spacing.

Consequently for all settings the total elastance of the two serially-connected capacitors is

$$(26) \quad S_T = S_1 + S_2 = N \frac{d}{A} + N \frac{D-d}{A} = N \frac{D}{A} \text{ (a constant)}$$

which satisfies Equation 14.

Precision loss measurements at radio-frequencies have been made using the adjustable conductance unit DG of Fig. 9. The detectors used were of readily available type: specifically a commercial Q-meter was used for parallel (conductance) substitutions: the circuitry and techniques are later more fully discussed in connection with Fig. 15.

With such differential loss standards, the time required for a measurement is only about two or three minutes as compared to about a half hour required for a measurement using the classical reactance-variation and susceptance-variation methods.

The differential-loss networks above described have many applications in the field of alternating-current measurements. Some of these applications are shown in Figs. 14 to 16.

For measurement of the effective conductance of an unknown G_X by the bridge method, the network P20 of Fig. 5a may be included in one arm of a Wheatstone bridge W2 (Fig. 14). The bridge is balanced twice, once with the network P20 alone in circuit, and once with the unknown G_X in shunt to network P20. The difference between the two values of effective conductance of network P20 for which the bridge is in balance is equal to the effective shunt conductance of the unknown G_X . Assuming the adjustable capacitors C_{P1} and C_{P2} are constructed and ganged as in discussion of Figs. 9 and 10 or 13, the two effective conductance values of network P20

may be read from dial 11G (Fig. 9), when calibrated in terms of conductance, or from a chart such as shown in Fig. 8.

For measurements of the effective conductance of an unknown G_x by the Q-meter or resonance method, the network P20 (Fig. 15) is connected in parallel to the capacitor C (or inductor L) of the series-resonant circuit L, C of the Q-meter. With circuit L, C tuned to resonance at the applied frequency and with a constant injection voltage (e), network P20 is adjusted as above described so that the value of voltage E is the same when the unknown conductance G_x is connected in shunt to network P20 as when the conductance G_x is out of circuit. The difference between the two values of the effective conductance G_e of network 20 for the two adjustments is therefore equal to the conductance G_x of the unknown. As in the case of the corresponding bridge method (Fig. 14), such two values of the effective conductance G_e may be read directly from dial 11G (Fig. 9) or from a chart similar to Fig. 8 provided that the capacitors C_{P1} , C_{P2} are ganged and constructed to provide a constant capacitance as seen at the terminals of the network P20.

In the bridge W4 of Fig. 16, each of two adjacent arms includes a composite network similar to network P20 of Fig. 5a whose effective shunt conductance is adjustable by a pair of oppositely adjustable capacitors. The four capacitors S_1 , S_2 , S_3 , S_4 of networks 1P, 2P are ganged as indicated by the threaded shaft and nut arrangement 70 for adjustment in unison by dial 11LG.

The adjustable capacitors are so constructed that for all settings of dials 11LG, the relation of their elastances may be expressed as

$$(27) \quad S_1 = S_3$$

$$(28) \quad S_2 = S_4$$

and

$$(29) \quad S_1 + S_2 = S_3 + S_4 = S_T$$

The two fixed resistors R_P of the networks 1P and 2P are of equal conductance value G_P .

It can be shown that the difference G_e between the effective shunt conductances of the two networks 1P, 2P may be expressed as

$$(30) \quad \Delta G_e = \frac{G_P \Delta S}{S_T}$$

where $\Delta S = S_1 - S_2 = S_3 - S_4$.

Thus, with bridge W4, the value of an unknown conductance G_x connected in parallel to one of said arms of the bridge may be determined by adjusting dial 11LG for balance. It is to be noted that the unknown conductance is determined by a single balance rather than by two as required by bridge W2 of Fig. 14. It is also to be noted that although the change in effective conductance of each of networks 1P, 2P follows a square law (Equation 18), the difference ΔG_e between their effective conductances is linear so that equal incremental changes of elastance afford equal incremental changes of the effective shunt conductance transferred from one to the other of the lower bridge arms under discussion.

If the unknown conductance is greater than the effective shunt conductance, preferably to the other arm of the bridge, a selected fixed standard conductance G_K may be connected in shunt to such other arm and dial 11LG adjusted for a single balance of the bridge. In such case, the value of the unknown conductance is

$$(31) \quad G_x = G_K + \Delta G_e$$

or

$$G_K = G_x + \Delta G_e$$

There is no ambiguity in application of Equation 31 as the sign of the incremental elastance change ΔS of Equation 30 becomes negative when dial 11LG is adjusted in the range for which S_2 and S_4 are greater than S_1 and S_3 . The dial 11LG may be directly calibrated in terms of ΔG_e , the positive and negative value increasing in opposite directions away from the setting for which all of the capacitors are of equal elastance value.

What is claimed is:

1. A two-terminal composite network providing values of effective shunt conductance (G_e) which are each essentially independent of frequency throughout a range of frequencies comprising two rudimentary networks connected in series between the two terminals of said composite network, the first of said rudimentary networks essentially consisting of a first parallel combination of fixed resistance R_{P1} and adjustable capacitance C_{P1} providing a Q of not less than 20 for said range of frequencies, the second of said rudimentary networks essentially consisting of a second parallel combination of fixed resistance R_{P2} and adjustable capacitance C_{P2} providing a Q of not less than 20 for said range of frequencies, said adjustable capacitances comprising adjustable condensers coupled for concurrent adjustment in opposite senses and whose plates are shaped to maintain constancy of the total elastance S_T of the composite network and which provide throughout their range of adjustment a total capacitance C_T such that the quotient

$$\frac{C_T}{G_e}$$

is greater than

$$35 \quad \frac{3.2}{F}$$

for the lowest frequency F of said range when G_e is in micromhos, C_T is the micromicrofarads and F is in megacycles, the effective shunt conductance (G_e) of said composite network for concurrent values of said adjustable condensers being

$$G_e = G_{P1} \left(\frac{S_{P1}}{S_T} \right)^2 + G_{P2} \left(\frac{S_{P2}}{S_T} \right)^2$$

where S_{P1} and S_{P2} are respectively concurrent values of the elastances of said adjustable capacitances C_{P1} and C_{P2} , and G_{P1} and G_{P2} are the values of the fixed resistances R_{P1} and R_{P2} .

50 2. A two-terminal composite network as in claim 1 in which one of said fixed resistances is of extremely high value to optimize the range of variation of the equivalent shunt conductance G_e of the composite network for the range of adjustment of capacitances C_{P1} and C_{P2} .
